UNITED STATES PATENT OFFICE.

ABEEL CANDA, OF CRANFORD, NEW JERSEY.

CARBURETER.

1,118,919.

Specification of Letters Patent.

Patented Dec. 1, 1914.

Application filed June 4, 1913. Serial No. 771,656.

To all whom it may concern:

Be it known that I, ABEEL CANDA, a citizen of the United States of America, and a resident of Cranford, in the county of Union and State of New Jersey, have invented certain new and useful Improvements in Carbureters, of which the following is a specification.

My invention relates to improvements in carbureters, and comprises means for insuring a more thorough mixture of air and combustible than is produced by present carbureters.

The object of my invention is to provide a more perfect mixture of air and combustible, and to do this in a simple manner and by simple means.

I will now proceed to describe my invention with reference to the accompanying drawings, wherein—

Figure 1 shows a transverse vertical section of one well known type of carbureter to which an air distributing device embodying my invention has been applied; Fig. 2 shows a similar section of another well known form of carbureter to which an air distributing device embodying my invention has been applied and Fig. 3 shows a side elevation of the mixing device removed from the carbureter.

It is well known that carbureters of the present day do not deliver to the engine a perfect mixture of air, and gasolene or kerosene, as a gas, but that the mixture is full of drops of liquid gasolene or kerosene; one reason being that the so-called "auxiliary air" is not properly mixed with the stream of atomized liquid and air at and beyond the point where the current of auxiliary air

joins the main or primary stream of air carrying misted gasolene or kerosene in suspension. Another reason is that, in practice, stratification occurs, in the carbureter and in the intake pipe of the engine, to a very

great extent. It is well known that gases of even slightly different specific gravities are very prone to stratification; that it is an extremely difficult matter to produce a fairly uniform mixture of two gases of somewhat different specific gravities. Now the specific gravity of gasolene vapor is much greater than that of air, and the specific gravity of air with liquid gasolene or kerosene in suspension is higher than that of gasolene vapor. Ordinarily, the auxiliary air is ad-

mitted at the side of the carbureter, and passes up into the engine intake at the side of the primary current of air with misted gasolene or kerosene in mechanical suspension, and without proper mixture with such primary current. The conditions existing in the ordinary carbureter are, therefore, particularly such as favor stratification as against thorough mixture; and this tendency to stratification is further enhanced in the ordinary carbureter, by the ordinary butterfly or throttle valve, which, commonly, is so placed as to favor passage of the auxiliary air up along one side of such throttle valve, and to favor the passage of the principal portion of the primary current of air with gasolene or kerosene in suspension along the other side of such valve.

By the present invention I provide a mixing device, applicable to ordinary carbureters, and to existing carbureters having the throttle valve placed as it commonly is, which mixing device produces a thorough mixture of the auxiliary air with the main or primary current of the mixed air and misted kerosene or gasolene. I have found that in practice, this air mixing device reduces considerably the consumption of fuel and increases noticeably the flexibility of operation of the engine.

Referring first to Fig. 1, numeral 1 designates the main air passage, or primary air passage, of the carbureter, 2 the spray nozzle, 3 the so-called carbureter bowl, 4 the float and 5 the float valve operated by that float.

6 designates the usual auxiliary air inlet, 7 the auxiliary air valve, and 8 the spring of said valve.

9 designates the throat through which the auxiliary air passes into the primary air passage 1.

10 designates the usual butterfly throttle valve.

It will be seen that, except as such tendency is prevented by means hereinafter described, there is a natural tendency for the primary air, carrying with it the atomized fuel from spray nozzle 2, to pass in large measure upon the left hand side of the valve 10, and for the auxiliary air to pass up on the right hand side of that valve, there being, therefore, a marked tendency for stratification in the engine intake to which the carbureter is connected (which intake is 110

not shown in the drawings, but may be understood to be connected, as usual, to the upper end of the carbureter). To obviate this tendency toward stratification, and to 5 produce a thorough mixture of the auxiliary air with the primary current of air with fuel vapor in suspension, I introduce into the carbureter a hollow shell 11, preferably perforated as shown, and preferably provided internally with a perforate cone 12. The side of the member 11 facing the throat 9 is preferably blank or imperforate, so that the auxiliary air is forced to pass around to the sides and back of the member 11 before 10 it can enter the interior of that member 11. The perforations of the member 11 are preferably of considerable size and placed well apart, both for mechanical strength of the member 11, and in order that these perforations 15 may act as individual nozzles, each projecting a jet of auxiliary air into the primary current of mingled air and fuel vapor passing up through the center of the member 11. Furthermore, since the perforations 20 of said member 11 are of considerable size, these perforations are not apt to become choked by dust or other foreign matter carried in with either air current. The perforate cone 12 serves to spread the primary 25 current of mingled air and fuel vapor, and discharges such primary current as a series of jets into the interior of member 11. Therefore, in the operation of the carbureter, there exists, above the cone 12, and 30 within the interior of the member 11 and in the space thereabove, and in the engine intake, a large number of more or less parallel and contacting jets of the primary current of mingled air and fuel vapor and of 35 the secondary air, which are in intimate contact with each other and, in passing up through the engine intake, naturally blend; the tendency to stratification of the primary 40 current along one side of the intake and of the secondary air current along the opposite side of the intake, being overcome, and a very intimate and uniform mixture of the air and fuel vapor being formed in the engine intake. Moreover, the perforate cone 45 12 tends to break up any drops of liquid fuel which might be carried with the primary air, the liquid which gathers on that cone having full opportunity to evaporate, or to split into smaller drops which can be 50 carried along by the primary current passing through that cone.

The member 11, provided with the perforate cone 12, is readily applied to existing carbureters by first removing the valve 10, 55 inserting said member 11, and then re-inserting the valve 10.

In order that the member 11 may be readily applicable to existing carbureters, the primary air passages of which are not, 60 as a rule, perfect'vsymmetrical in the vicinity

of the throat 9, said member 11 is provided, on the side facing the auxiliary air passage, with a depending portion 13.

My device is applicable to most, if not all, of the existing types of carbureters. It will be understood that slight changes in form and proportions may be necessary for different makes of carbureters. However, many of the standard forms of carbureters may receive a member 11 of one design; and in Fig. 2 I illustrate such member 11 applied to another well known form of carbureter which in its action is practically the same as that of the carbureter shown in Fig. 1, corresponding reference characters being 70 used in both Figs. 1 and 2 to designate like parts of the two carbureters shown.

What I claim is:—

1. An air and vapor mixing device for carbureters, comprising a hollow member 85 adapted to be placed within a carbureter, at the intersection of the primary and auxiliary air passages of the carbureter, one side of said member, adapted to face the auxiliary air passage of the carbureter, being 90 blank, other sides of said member being provided with openings for the passage of the auxiliary air into mixture with the primary current passing through that member.

2. An air and vapor mixing device for 95 carbureters comprising a hollow member adapted to be placed within a carbureter, at the intersection of the primary and auxiliary air passages of the carbureter, said member adapted for the flow through it of 100 the primary current, and being provided with openings for the passage of the auxiliary air into mixture with the primary current passing through that member, said member having within it primary-current- 105 diffusing means comprising a perforate conical member tapering in the direction of flow of the primary current.

3. The combination with a carbureter having 110 communicating passages for primary and auxiliary air respectively, and having means for injecting fuel into the primary air, prior to the entry of the auxiliary air into the primary air passage, of a mixing device located at the intersection of the primary and auxiliary air passages, and comprising a hollow member adapted for longitudinal flow through it of the primary air and having a blank side facing the auxiliary air passage, other sides of said member being provided with openings for the passage of the auxiliary air into mixture with the primary current passing through that member.

4. The combination with a carbureter having 115 communicating passages for primary and auxiliary air respectively, and having means for injecting fuel into the primary air, prior to the entry of the auxiliary air into the primary air passage, of a mixing 120 125 130

device located at the intersection of the primary and auxiliary air passages, and comprising a hollow member adapted for longitudinal flow through it of the primary air, said member being provided with openings for the passage of the auxiliary air into mixture with the primary current passing through that member, said member having within it primary-current-diffusing means comprising a perforate conical member tapering in the direction of flow of the primary current.

5. The combination with a carbureter having communicating passages for primary and auxiliary air respectively, and having means for injecting fuel into the primary air, prior to the entry of the auxiliary air into the primary air passage, of a mixing device located at the intersection of the primary and auxiliary air passages, and comprising a hollow member adapted for

longitudinal flow through it of the primary air, said member being provided with openings for the passage of the auxiliary air into mixture with the primary current passing through that member, said member having within it a perforate cone extending across the interior of said member and adapted to divide and diffuse the primary current passing through said member, said cone tapering in the direction of the flow of the primary current, the base of said cone being near that side of the auxiliary air passage which is nearest the inlet for the primary air.

10 In testimony whereof I have signed this specification in the presence of two subscribing witnesses.
